EARRING

Gretyl Howard, 612 7th St., Sioux City, Iowa

Filed Dec. 22, 1959, Ser. No. 58,762

Term of patent 14 years

(Cl. D45—9)

Fig. 1.

Fig. 2.

Fig. 3.

Fig. 4.

Fig. 1 is a side view of an earring showing the new design, one manner of attaching an ornament being shown in broken lines;

Fig. 2 is a front view of the earring of Fig. 1;

Fig. 3 is a top plan view thereof; and

Fig. 4 is a side perspective view of the earring on a reduced scale, and showing in broken lines another manner of attaching an ornament.

The dominant features of my design reside in the portions shown in full lines.

I claim:

The ornamental design for an earring, as shown and described.
